UNITED STATES PATENT OFFICE.

HUGO C. RASSMANN, OF BEAVER DAM, WISCONSIN.

WATERING DEVICE FOR CATTLE.

1,260,804.

Specification of Letters Patent. Patented Mar. 26, 1918.

Application filed February 12, 1917. Serial No. 148,138.

To all whom it may concern:

Be it known that I, HUGO C. RASSMANN, a citizen of the United States, and a resident of Beaver Dam, in the county of Dodge and 5 State of Wisconsin, have invented certain new and useful Improvements in Watering Devices for Cattle; and I do hereby declare the following to be a full, clear, and exact 10 description of the invention, such as will enable others skilled in the art to which it appertains to make and use the same.

This invention relates to improvements in watering devices for cattle, and particularly to such as embody means operable by the 15 cattle to control the flow of water into the bowl,—one object of my present invention being to provide a structure in which the bowl shall be supported independently of the fount or water supply means, whereby the 20 liability of breakage shall be reduced to a minimum, and whereby shipment of the structure shall be facilitated.

With this and other objects in view, the invention consists in certain novel features 25 of construction and combinations of parts as hereinafter set forth and pointed out in the claims.

In the accompanying drawings, Figure 1 is a side elevation of watering device structure embodying my improvements, and Fig. 30 2 is a bottom plan view, partly in section.

1 represents a vertical water pipe with which suitable means may be connected, at either of its ends, for conveying water thereto. A valve casing 2 is provided on the pipe 1 and may be made integral therewith,—said valve casing being adapted to communicate with the water pipe and being made with a 35 discharge outlet at 3, to deliver water into 40 a bowl 4 located under the same. The pipe 1 and casing 2 thus constitute a fount for supplying water to the bowl. A valve (not shown) is located within the casing 2 for controlling the passage of water therethrough, and this valve may be constructed as 45 illustrated in my previous Patent No. 1,210,693, issued January 2nd, 1917, with its stem 5 projecting above the casing.

The bowl 4 is pivotally connected near its 50 bottom with one end of a bracket 6 and is maintained in its normal horizontal position by means of a pivoted latch 7 disposed between the upper edge of the bowl and the bottom of the casing 2. In the present instance, I have shown this latch pivoted to

the casing 1 and adapted at its free end to engage the bowl.

The bracket 6 may comprise two arms 8 having alining perforated bosses 9 at one end to receive a pivot pin 10, the latter also 60 passing through spaced lugs 11 projecting from the bottom portion of the bowl. At their other ends, the arms forming the bracket 6 are adapted to connect with a support which is independent of the fount. In 65 the present instance, I have shown the arms of the bracket so formed as to provide a clamp 11^a to engage a stall post 12 and secured in place thereon by means of bolts 13, 14. In the drawings I have shown a 70 metal stall post to which the bowl-supporting bracket is clamped, but it will be understood that the bracket 6 may be so formed as to adapt it for attachment to a wooden or even concrete portion of the stall structure. 75

In the present instance, the arms 8 forming the bracket 6 are formed between their ends with semi-circular enlargements or bowed portions 15 which embrace the vertical pipe 1 of the fount and to prevent these portions of the bracket from clamping said pipe, the bracket arms may be formed with abutting shoulders 16, as illustrated in Fig. 80

2. The pipe 1 may be provided near its 85 lower end and at diametrically opposite sides with pairs of spaced lugs 17 between which the bowed portions 15 of the bracket arms will pass, so that the bracket may be accurately located to cause the bowl to be 90 properly positioned to be engaged by the latch 7.

The valve within the casing will be controlled by the action of the animal, and the means for this purpose may comprise a lever 95 18 provided with a platform 19 located within the bowl, said lever being pivoted to the water pipe above the casing 2 and provided with a part 20 to engage the valve stem, all as fully shown and described in 100 patent granted to me on the 7th day of November, 1916, and designated by No. 1,204,066.

With the construction and arrangement herein shown and described, the bowl will 105 be pivotally mounted independently of the fount, and thus liability of breakage of the latter and the consequence of such breakage, will be reduced to a minimum.

Various changes might be made in the de- 110

tails of construction of my invention without departing from the spirit thereof or limiting its scope and hence I do not wish to restrict myself to the precise details herein set forth.

Having fully described my invention what I claim as new and desire to secure by Letters-Patent, is:—

1. In a watering device for cattle, the combination with a fount and a bowl to receive water therefrom, of a bracket constructed at one end for attachment to a support independent of the fount, and pivotally connected at its other end with the bowl, and a latch engaging the upper portion of the bowl and the fount.
2. In watering means for cattle, the combination with a fount, and a bowl to receive

water therefrom, of a bracket comprising two arms coöoperating at one end to provide attaching means to a support independent of the fount and pivotally attached at their other ends to the bowl, said arms having intermediate bowed portions to accommodate a portion of the fount, guide lugs on the fount between which said bowed portions of the bracket arms pass, and means for retaining the bowl in a normal horizontal position.

In testimony whereof, I have signed this specification in the presence of two subscribing witnesses.

HUGO C. RASSMANN.
